UNITED STATES PATENT OFFICE

110,607

DESIGN FOR A TEXTILE FABRIC

Jean Guy Donadieu, New York, N. Y.

Application November 15, 1937, Serial No. 72,902

Term of patent 3½ years

To all whom it may concern:

Be it known that I, Jean Guy Donadieu, a citizen of the United States of America, residing in the city of New York, State of New York, have invented a new, original, and ornamental Design for a Textile Fabric, of which the following is a specification, reference being had to the accompanying drawing, forming part thereof, wherein,

I claim:

The ornamental design for a textile fabric, substantially as shown.

JEAN GUY DONADIEU.
